UNITED STATES PATENT OFFICE.

ALVIS E. LEWIS AND WILLIAM R. COSBY, OF EVANSVILLE, ARKANSAS.

CAR-COUPING.

SPECIFICATION forming part of Letters Patent No. 437,761, dated October 7, 1890.

Application filed July 23, 1890. Serial No. 359,637. (No model.)

To all whom it may concern:

Be it known that we, ALVIS E. LEWIS and WILLIAM R. COSBY, citizens of the United States, residing at Evansville, in the county 5 of Washington and State of Arkansas, have invented certain new and useful Improvements in Car-Couplers; and we do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 Our invention has relation to car-couplers; and it consists in the novel construction and arrangement of its parts.

In the accompanying drawings, Figure 1 is a perspective view of the end of a car with 20 our invention attached thereto. Fig. 2 is a sectional view of the coupler. Fig. 3 is a view of part of the bottom of the car with our invention attached thereto.

25 Our invention is described as follows: We cast a bulk-head A, with the elongated neck a, a deep throat a', with enlargements in its top and bottom, an elongated slot a², perforations a³ a⁴ a⁵, and shoulders e and e'.

In the slot a² is securely fixed by a band B 30 one end of a spring-rod b, having an L-extension b'. The other end of said spring passes forward and terminates in a hook b², which passes down through the slot a³ and enters the slot a⁴. The front edge of said hook rests 35 firmly against the front walls of the slots a³ and a⁴, which are cut on a circle. Said hook is provided on its top with an eye b³. Through the perforation a⁵ is driven a plug a⁶, the ends of which extend beyond the diameter of 40 the elongated neck for some little distance on each side.

The bulk-head and its attachments are placed in a box C, which is attached to the bottom of the car. The bottom of said box is 45 open, and on its inside are secured the lugs c and c', against which rest the shoulders e' and plug a⁶, respectively, and said box is braced on its bottom by a plate c² and a guide c³, which passes through a staple c⁴ on the 50 bottom of the bulk-head. (See Fig. 3.) Said bulk-head is further provided with a bumper-spring c⁵, one end of which rests against the

lugs c' and the other presses against the rear edge of the band B on the bulk-head. This keeps the front edge of the band B and the 55 plug a⁶ against the rear edge of the lugs c and c', respectively. The mouth of the box C is sufficiently wide to admit of a sway from side to side in the bulk-head as the cars go around curves. 60

To raise the hook b², we have a chain attached to the eye b³. Said chain can be worked by either a lever on the top of the car or by a roller and wheel fixed a convenient height so that it can be reached by a person standing 65 on the ground and not between the cars.

Our invention is operated as follows: In the bulk-head of an adjoining car we place a link, then back the car and let the link enter the mouth of bulk-head A. When the link strikes 70 the inclined edge of the hook b², said hook will fly up and admit the link to the throat of the bulk-head. When the link is in, the hook will fly back in place and act as a pin. Said link can be released either from the top of the 75 car by pressing on the free end of the lever or from the ground by winding the chain around the roller on the end of the car. Should we wish to couple with a low car, we let the inner end of the link rest in the upper enlargement of the throat of the bulk-head and let the other end extend downward through the mouth of said bulk-head, and should we wish to couple with a high car we let the inner end of the link fall in the lower enlargement and the outer end extend upward 80 through the mouth of said bulk-head. 85

With this coupler any of the links now used on railroads may be used, or a curved link D may be used with great convenience when 90 coupling with higher or lower cars.

Having described our invention, what we claim as new, and desire to secure by Letters Patent, is—

1. A car-coupler consisting of the bulk-head A, band B, spring b, hook b², and plug a⁶, substantially as shown and described, and for the purposes set forth. 95
2. In a car-coupler, the combination of the bulk-head A, band B, spring b, hook b², box C, lugs c and c', brace c², and spring c⁵, substantially as shown and described, and for the purposes set forth. 100
3. The combination of the bulk-head A, hav-

ing in its throat the enlargements described and in its head the perforations a^3 and a^4 and extending along its upper face a slot a^2 , ending in a depression d , shoulders e e' , and in its neck the perforation a^5 , spring b , having the L-extension fitting in the depression d and the hook b^2 working in the perforations a^3 and a^4 and the eye b^3 , band B , securing the rear end of spring b firmly in the said slot a^2 and depression d , box C , secured to the bottom of the car, having the lugs c and c' , against which latter rests the plug a^6 and

shoulders e' , guide c^2 , secured to said box, and staple c^4 , passing over said guide and having each end secured to the lower face of said 15 bulk-head, all substantially as shown and described, and for the purposes set forth.

In testimony whereof we affix our signatures in presence of two witnesses.

ALVIS E. LEWIS.

WILLIAM R. COSBY.
